To all whom it may concern:—

Be it known that I, Nicholas S. Veder, of the City of Troy, in the County of Rensselaer and State of New York, have invented or produced a new and original Design for a Cooking Stove, of which the following is a full, clear and exact description, reference being had to the accompanying photograph of a cooking stove embodying my said design.—

This design may be distinguished from all others by having, within a compound border moulding, &c, a certain compound ornament &c, on the panel of the large door plate R, and a certain compound ornament &c, on the panel-plate or plates T, of a stove; the same being shaped and arranged so as to appear as represented by the aforesaid photograph.—

What I claim as my invention or production and desire to secure by Letters Patent is the design of the plates R and T, of a stove, as herein set forth.

Witnesses.
